AIR CLEANER STACK ASSEMBLY AND
MOUNT FOR TRACTORSAndy M. Rustemeyer, Rte. 1, Box 18,
Creston, Wash. 99117

Filed Nov. 19, 1971, Ser. No. 200,659

Term of patent 3½ years

Int. Cl. D12—09

U.S. Cl. D14—6 A

FIG 1

FIG 2

FIG. 1 is a perspective view of an air cleaner stack assembly and mount for tractors showing my new design;
FIG. 2 is a top plan view thereof;

FIG. 3 is a side elevational view thereof; and
FIG. 4 is a front elevational view thereof.

The fragmentary broken line showing of the tractor in the drawing is for illustrative purposes only.

I claim:

The ornamental design for an air cleaner stack assembly and mount for tractors, as shown and described.
